THREAD ADVANCING REEL

Dean H. Brownell, Enka, N. C., assignor to American Enka Corporation, Enka, N. C., a corporation of Delaware

Application June 28, 1948, Serial No. 35,672

11 Claims. (Cl. 28—71.7)

1

This invention relates to thread-storage, thread-advancing devices, and more particularly to a reel having a plurality of yarn-supporting bars each of which is successively moved axially for a limited distance from a starting position in the direction of yarn travel and is then radially retracted from yarn-supporting position and moved axially back to the starting position.

Reels of the foregoing type are known to the art, but the mechanisms heretofore employed for radially moving the bars to and from the yarn-supporting position have been so cumbersome and difficult to maintain as to preclude their use on a commercial scale. For example, they include cam means for reciprocating the bars, means for guiding the bars for extension to and retraction from yarn-supporting position, means for supporting the bars, and separate means for positively moving the bars to and from yarn-supporting position. Accordingly, a cantilever construction is not possible and threading difficulties are encountered.

In an effort to overcome the foregoing difficulties, a reel has been developed in which an inflated resilient tube underlies each bar and holds it in extended or thread-supporting position. The bar is retracted by evacuating the inflating gas from the tube. This scheme does involve a normally retracted bar so that positive movement is required only in the extending operation and it does involve the support of the bar by the resilient tube that moves it. There is no elimination of parts, however, due to the fact that the rod-supporting tubes themselves require support. Furthermore, because of this, the cantilever construction is not achieved.

It is therefore an object of this invention to provide a cantilever reel of the reciprocating retractile bar type which is characterized by a large reduction in the number of parts required to effect the necessary movements, the protection of all moving parts against any liquids that may be employed in treating threads supported and advanced on the reel, and the complete elimination of the necessity for any pneumatically or hydraulically operated parts.

It is a more specific object of this invention to provide a single means that supports the rods in both the extended and retracted position and effects the extending and retracting operations.

2

Another object of this invention is to provide a reel that is self-cleaning and self-threading so that the initial threading-up operation is rendered extremely simple.

5 Other objects and advantages of this invention will be apparent upon consideration of the following detailed description thereof in conjunction with the annexed drawings wherein:

Figure 1 is a view in side elevation of a reel 10 constructed in accordance with the teachings of the present invention;

Figure 2 is an end view of the reel of Figure 1; Figure 3 is a view in vertical section taken along the line 3—3 of Figure 2;

15 Figure 4 is a cross sectional view taken along the line 4—4 of Figure 3;

Figure 5 is a view in side elevation of the rod-supporting and moving cam that constitutes a part of the present invention;

20 Figure 6 is a view in end elevation showing one face of the cam assembly of Figure 5;

Figure 7 is a top plan view of the cam assembly of Figure 5;

Figure 8 is a fragmentary vertical sectional view of a modified thread-storage, thread-advancing device constructed in accordance with the principles of the present invention; and

Figure 9 is a view in section taken along the line 9—9 of Figure 8.

25 Referring now in greater detail to the drawings, and in particular to Figures 1 to 4 thereof, the numeral 10 represents the thread-supporting and advancing bars of which the reel is made. As shown in Figures 2 and 4, the reel may be

30 comprised of twenty bar members 10. These bar members are maintained in circumferentially-spaced relationship and are guided for independent radial movement by a circular plate 11 and housing 19, each of which being provided with twenty equally-spaced radial slots at 12 and 12b, respectively.

35 While the bars 10 are maintained in spaced relation and are guided for independent radial movement by the plate 11, they are actually supported by a cam assembly 13 of a construction which will be apparent upon reference to Figures 5, 6 and 7. The cam assembly 13 includes a central hub portion 14 which is supported by an end

40 15 of a supporting shaft 16 which is suitably mounted in any convenient manner not shown.

Since the supporting shaft 16 is rigidly held and it rigidly holds the cam assembly 13, it is apparent that the cam assembly functions as a bearing support for the plate 11. In this arrangement, the plate 11 is provided with a central socket at 17 which receives a projection or boss 18 constituting an integral part of the cam assembly 13. Thus, the shaft 16 through its end 15 supports the cam assembly 13 which through its projection 18 supports the plate 11 for rotation around and with respect to the cam assembly.

The cam assembly 13 includes four cam faces 19, 20, 21 and 22. The cam faces 19 and 20 lie in planes parallel to the planes of the bars 10 and are formed at the periphery of two disc-like members 23 and 24 extending from the hub 14 of the cam assembly 13. Each bar member 10 is provided with sockets 25 and 26 and bearing guides 27 and 28. Cam-following rollers 29 and 30 are mounted in each of the sockets 25 and 26, respectively, on a shaft or pin 31 which passes through and is supported from the bearing surfaces at 27 and 28. Each roller 29 rests against the cam surface 19 of the disc 23 while each roller 30 rests against the cam surface 20 of the disc 24. It can now be seen that the bars 10 through their rollers 29 and 30 are free to rotate around the axis of the shaft 16 with the cam followers 29 and 30 in contact with cam faces 19 and 20, respectively. In order to bias the cam followers 29 and 30 into continuous contact with the cam faces 19 and 20, grooves are cut in the outer surfaces of each of the bars 10, and these grooves are occupied by resilient bands 32 and 33 which draw all of the bars 10 together inwardly against the faces 19 and 20. The structure and function of the bands 32 and 33 and the grooves in the bars 10 in which the bands operate are clear upon reference to Figure 4. Note in particular that the grooves vary or alternate in depth as between adjacent bars 10. In other words, the bar 10 at the top of Figure 3 has a shallow groove accommodating the band 32 and a deep groove accommodating the band 33. The two adjacent bars, however, have deep grooves accommodating the band 32 and shallow grooves accommodating the band 33.

In addition to the cam followers 29 and 30 which have been described above, each bar 10 is also provided on its shank portion with cam-following surfaces 34 and 35 which coat, respectively, with cam faces 21 and 22 of the cam assembly 13.

It is apparent that before the structure described can function as a thread-storage, thread-advancing device, it is necessary to impart a rotary movement to the bars 10 about a common central axis, such as the axis of the shaft 16. This is accomplished by means of a pulley 36 which is mounted on bearings 37 and 38 for rotation with respect to the shaft 16. The pulley 36 is made integral with housing 39 which surrounds all of that portion of the bars which lies to the right of the plate 11 as the assembly is viewed in Figure 3. The extreme left edge of the housing 39 is attached to the plate 11 so that the plate may be rotated by rotation of the housing.

If, now, reference is made to the contours of the cam surfaces 19, 20, 21 and 22, it will be seen how the illustrated device functions to store thread and advance it in a generally helical path toward the unsupported ends of the bars. The cam surface 21 is of such configuration that for a zone of 330.5° the bars are gradually moved

outwardly or to the left of Figure 1 as a result of the gradual advance of the cam face 21 from point *a* to point *b* in a clockwise direction (see Figures 6 and 7). In a remaining zone of 29.5° (see Figure 7), the cam face 21 recedes axially to the same extent that it extends in the clockwise direction from *a* to *b*. Thus, each bar in 360° of movement about the axis of shaft 16 is gradually advanced toward the unsupported end of the apparatus and is quickly retracted. Actually, the cam face 21 moves the bars toward the unsupported end of the apparatus, and the cam face 22 which is complementary to the cam face 21 returns them to the starting position. Thus, the bars are moved to the left by the cam face 21 and are returned to the right by the cam face 22. Since the thread is in contact with the bars 10 (see Figure 1), it will move with them as they move and will build up a helix as shown in Figure 1 due to the movement of the bars toward their unsupported ends.

While the return movement of the bars is effected, they must be out of contact with the thread, so that the helix can be maintained. To this end, the cam surfaces 19 and 20 coating with the resilient bands 32 and 33 effect retraction of each bar radially as it moves from *b* to *a* in a clockwise direction so that as each bar is retracted axially it is held out of contact with the thread. The position assumed by the bars during their retraction is clearly shown at the top of Figure 2, the action being brought about by the notch in the cam surfaces 19 and 20. The notch is so arranged that for 11.5° of movement the bar is moving inwardly, and after 18 more degrees of movement it is back in the radial sense to the starting position. Meanwhile, the concurrent action of the cam face 22 has been to restore it to the axially retracted position.

It will now be apparent why the grooves which receive the bands 32 and 33 must vary in depth. When the cam followers 29 and 30 of any given bar 10 are passing through the 29.5° dip in sections of the cam surfaces 19 and 20, the polygon defined by the cross section of the whole reel has its face at the point of dip twice as long as all of the other faces due to the retraction of that one bar from the normally radially extended position. If the grooves receiving the bands 32 and 33 were all of equal depth, the recession of the bar into the dip in cam surfaces 19 and 20 would result merely in the movement of the bar into a position where it would lie beyond the restraining influence of the band and where it could wobble. This is due to the fact that the band would stretch in a straight line between the two adjacent bars across the bar following the dip without touching it. If, however, one groove of each adjacent bar is deeper than the corresponding groove of the bar which is in the dip in the cam surface it is apparent that there will still be a thrust component exerted radially inwardly from the band and acting on the retracted bar which is following the dip at that particular moment. This will be clear upon reference to Figure 4 wherein bar 10b is following the dip and bars 10c and 10d are beside it. The band 33 which is in shallow grooves in bars 10d and 10c and in a deep groove in bar 10b does no work while the band 34 which is in a deep groove in bars 10d and 10c exerts thrust on bar 10b and maintains its position despite the contour of the cam. This construction has the further advantage that the bars can be rotated at much higher R. P. M.'s without affecting the efficiency

of the reel and therefore the delivery speed of the reel is only limited to the extrusion speed of the threads.

It will be understood that a thread-storage, thread-advancing device such as that which constitutes the subject matter of this invention finds a primary utility in supporting and advancing freshly spun rayon yarn while it is subjected to aftertreating liquids for such purposes as washing out spin bath acids, desulfurizing, and applying a finish. Consequently, the bars 10 which support the thread during these treatments are exposed to the action of the treating liquids. Since some of the treating liquids are corrosive in nature, it is an important feature in this invention that the moving parts of the apparatus which effect the propulsion and manipulation of the bars previously described can be and are wholly protected from the action of these liquids. The manner in which this is done can best be understood by reference to Figures 8 and 9 wherein there is shown a rubber or other resilient cap member 40 that surrounds the edge of the housing 39a adjacent the plate 11a and includes individual boots 41 surrounding each bar member 10a adjacent the point where the bar member passes through the slots 12a in the plate 11a and slots 12c in housing 39a. Because of the resiliency of the boot 41, it can follow the movement of the bar as it is extended and retracted both axially and radially. It will be noted that the bars 10a are provided with a rounded portion at that portion of their length which projects from the housing 39a so that a boot of circular cross section can be tightly seated thereagainst. The remaining parts shown in Figure 8 correspond in structure and function to the like parts of the preceding figures and need not be described again.

While the shaft 16 has been indicated as a stationary shaft, it is preferably apparent that that shaft may be rotated independently of the rotation of the pulley 36, and that independent rotation of the pulley 36 and shaft 16 will vary the frequency at which the operation of the bars takes place. In general, as the shaft 16 turns with the pulley 36, the frequency of the described operations decreases as the speeds approach equality. On the other hand, when the two are turned in opposite directions, an increase in frequency results. Since the cyclic operation of the apparatus produces the helix angle of the thread supported on the thread-storage, thread-advancing device, it is apparent that by manipulation of the speed and direction of the shaft 16 relative to that of pulley 36, the helix angle is subject to infinite adjustment so that any desired quantity of thread may be supported on the reel at any one time, irrespective of the take-up rate of the reel as a whole. Thus, the storage time, or the time that any length of thread is on the reel, is entirely within the control of the operators.

While this invention has been described with respect to but a few embodiments thereof, it is to be understood that the description is exemplary rather than limiting in nature, and is intended to demonstrate the invention in such terms that those skilled in the art may have an understanding of the principles thereof from which various modification in details of construction may naturally flow.

What is claimed is:

1. A thread-storage, thread-advancing device comprising a member having a plurality of radial slots therein, means to rotate said member, a bar in each slot of said member, each bar having a

thread contacting portion extending in one direction from said member and a shank portion extending in the other direction from said member, resilient means acting on the shanks of said bars to bias the bars toward a radially retracted position, means in the path of movement of the shanks of said bars to hold all but one of them in a radially extended position against said bias, and means acting on the shanks of said bars for gradually, successively moving said bars longitudinally in one direction as they rotate in the position of radial extension and for moving each bar successively longitudinally an equal distance in the opposite direction when it is in the radially retracted position.

2. A thread-storage, thread-advancing device comprising a plurality of bars each including a thread contacting portion and a shank portion, means for holding said bars in circumferentially-spaced relation for independent radial movement with all of the shank portions extending in one direction from said holding means, means for rotating said holding means, a pair of axially spaced cams both acting on said shanks to guide each bar in its rotation through a path which includes a radially extended portion and a radially retracted portion, resilient means acting on said shanks between said cams for maintaining shank-cam contact, and means acting on said shanks for moving said bars axially in one direction while they are in extended position and in the other direction while they are in retracted position.

3. A thread-storage, thread-advancing device comprising a plurality of bars each including a thread contacting portion and a shank portion, means for holding said bars in circumferentially-spaced relation for independent radial movement with all of the shank portions extending in one direction from said holding means, means for rotating said holding means, cam means including a pair of axially spaced surfaces acting on said shank portions for guiding each bar in its rotation through a path which includes a radially extended portion and a radially retracted portion, resilient means acting on said shank portions to maintain said shank portions in contact with said surfaces, said cam means also including surfaces acting on said shank portions for positively moving said bars axially in one direction while they are in extended position and in the other direction while they are in retracted position.

4. A thread-storage, thread-advancing device comprising a plurality of bars, means for holding said bars in circumferentially-spaced relation for independent radial movement, bar-supporting means to guide each bar in its rotation through a path which includes a radially extended portion and a radially retracted portion, the extended portion being substantially eleven times as long as the retracted portion, means for moving said bars axially in one direction while they are in extended position and in the other direction while they are in retracted position, a housing, means for rotating said housing, said holding means being connected to said housing for rotation therewith, said housing surrounding said bar-supporting means and the means for moving said bars axially whereby to protect them against the action of any liquids that may be used with threads supported and advanced by the device.

5. A thread-storage, thread-advancing device comprising a plurality of bars, means for holding said bars in circumferentially-spaced relation for independent radial movement, means for

rotating said holding means, and bar-supporting means including cam surfaces for guiding each bar in its rotation through a path which includes a radially extended portion and a radially retracted portion, said bar-supporting means also including cam surfaces for moving said bars axially in one direction while they are in extended position and in the other direction while they are in retracted position, said bar-supporting means being located at one end of the device whereby to provide a cantilever construction.

6. A thread-storage, thread-advancing device comprising a plurality of elongated elements comprising a reel, each element including a thread contacting portion and a shank portion, means to rotate the reel and means in the path of movement of the shank portion of the reel elements and coacting with the shank portions thereof for displacing the elements axially in one direction during the major portion of a revolution of the reel and for successively displacing them axially in the other direction during the remainder of a revolution thereof, and means also acting on said shank portions for successively retracting each element from and returning it to the path of rotation of the remaining bars of the reel during said remainder of a revolution of the reel.

7. A thread-storage, thread-advancing device comprising a plurality of elongated elements, a disc, means to rotate said disc, said disc having therein a plurality of radial slots equally spaced circumferentially, said elements between their ends being located in the slots of said disc to define a reel of polygonal cross section extending in one direction from said disc, each element including a first and a second pair of cam-following surfaces on the portion thereof extending in the other direction from the disc, an assembly movable with respect to said disc and presenting a first pair of axially spaced cam surfaces and a second pair of axially spaced cam surfaces parallel to the reel axis, said first pair of cam surfaces coacting with said first pair of cam-following surfaces to displace the elements axially and said second pair of cam surfaces coacting with said second pair of cam-following surfaces to displace said elements radially in and out from the reel surface, said first pair of cam surfaces being of a contour to produce gradual movement of the reel-defining portions of the elements in a direction away from the disc during the major portion of a cycle of relative rotation between the disc and said assembly and a successive return of said reel defining portions of said elements during the remainder of said cycle, said second pair of cam surfaces being of a contour to produce a radial inward and outward cycle of movement of each element in timed relation with the return portion of said cycle of relative rotation.

8. A thread-storage, thread-advancing device comprising a plurality of elongated elements, a housing surrounding a common end of said elements, said housing including a radially slotted disc for locating the elements in circumferentially-spaced relation with one of the elements projecting from the housing through each slot to define a reel, that portion of each element which lies within the housing including axially spaced cam-following surfaces, a pair of axially spaced cams mounted within the housing, resilient means biasing the cam-following surfaces of said elements against said cams in a plane located between the cams so that the cams sup-

port the elements, means for rotating said housing relative to said cams, and means for supporting said cams from a point without the housing, the contours of said cams being such that as the housing is rotated each element is, from a starting position, gradually displaced in an axial direction away from the housing and is then suddenly retracted and simultaneously displaced radially inwardly to its starting position.

9. A thread-storage, thread-advancing device comprising a plurality of elongated elements, a housing surrounding a common end of said elements, said housing including a radially slotted disc for locating the elements in circumferentially-spaced relation with one of the elements projecting from the housing through each slot to define a reel, that portion of each element which lies within the housing including axially spaced cam-following surfaces, a pair of axially spaced cams mounted within the housing, resilient bands surrounding said elements in planes between the cam-following surfaces to bias the cam-following surfaces of said elements inwardly against the respective cams so that the cams support the elements, means for rotating said housing relative to said cams, and means for supporting said cams from a point without the housing, the contours of said cams being such that as the housing is rotated each element is, from a starting position, gradually displaced in an axial direction away from the housing and is then suddenly retracted and simultaneously displaced radially inwardly to its starting position.

10. A thread-storage, thread-advancing device comprising a plurality of elongated elements, a radially slotted disc for locating the elements in circumferentially spaced relation with one of the elements extending through each slot from one side of the disc to define a reel, that portion of each element which lies on the other side of the disc including axially spaced cam-following surfaces, a pair of axially spaced cams, means for supporting said cams, each of said elements having a pair of grooves between its cam-following surfaces, said pairs of grooves lying in circumferential registry with the corresponding pairs of the other elements but alternating in depth as between adjacent elements in a common circumferential path, resilient bands seated in said grooves and surrounding said elements to bias the cam-following surfaces inwardly against the respective cams so that the cams support the elements, and means for rotating said disc relative to said cams, the contours of said cams being such that as the disc is rotated the reel defining portion of each element is, from a starting position, gradually displaced in an axial direction away from the disc and is then suddenly retracted and simultaneously displaced radially inwardly to its starting position.

11. A thread-storage, thread-advancing device comprising a plurality of elongated elements, a housing surrounding a common end of said elements, said housing including a radially slotted disc for locating the elements in circumferentially spaced relation with one of the elements projecting from the housing through each slot to define a reel, that portion of each element which lies within the housing including axially spaced cam-following surfaces, a pair of axially spaced cams mounted within the housing, each of said elements having a pair of grooves between its cam-following surfaces, said pairs of grooves lying in circumferential registry with the corresponding pairs of the other elements but al-

ternating in depth as between adjacent elements in a common circumferential path, resilient bands seated in said grooves and surrounding said elements to bias the cam-following surfaces inwardly against the respective cams so that the cams support the elements, means for rotating said housing relative to said cams, and means for supporting said cams from a point without the housing, the contours of said cams being such that as the housing is rotated each element is, from a starting position, gradually displaced in an axial direction away from the housing and is then suddenly retracted and simultaneously displaced radially inwardly to its starting position.
